by *W. C. Wood*,
Attorney.

UNITED STATES PATENT OFFICE.

WILLIAM CLARK WOOD, OF BROOKLYN, NEW YORK, ASSIGNOR TO THE
LEWIS & FOWLER GIRDER RAIL COMPANY, OF SAME PLACE.

STREET-RAILWAY TRACK.

SPECIFICATION forming part of Letters Patent No. 511,068, dated December 19, 1893.

Application filed April 6, 1893. Serial No. 469,273. (No model.)

To all whom it may concern:

Be it known that I, WILLIAM CLARK WOOD, a citizen of the United States of America, and a resident of Brooklyn, in the State of New York, have invented a new and useful Improvement in Street-Railway Tracks, of which the following is a specification.

This invention relates to a girder-rail track in which box-rails and clamp-chairs are employed in the curves and straight track, either or both, and consists in a novel switch-casting, adapted to be supported by clamp-chairs constructed on the same principle as those of the rails, and further adapted to be coupled endwise to adjoining box-rails in a peculiar and advantageous manner, and in certain novel combinations of parts, as hereinafter more fully set forth.

The objects of the invention are to adapt the switches to be made of cast-steel or of cast-iron, without unnecessary weight, and without any departure from the box-rail system of chairs and clamps; to adapt the tongue of a tongue-switch of this construction to be strongly pivoted to the switch-casting by means of a simple keyed pin, and to adapt such switch-castings to be readily and tightly coupled endwise to adjoining box-rails, or to one or more of such rails, by clamping devices similar in part to those of said clamp-chairs, and so that the rail-ends shall be solidly supported beneath by the switch-casting itself, so as to form smooth joints between the switches and the adjoining rails.

A sheet of drawings accompanies this specification as part thereof.

Figure 1 of the drawings is a small-scale plan view of a portion of a street-railway track, comprising a tongue-switch, which illustrates the present invention. Fig. 2 is a bottom view of the switch-casting, projected from Fig. 1. Fig. 3 represents a vertical cross-section at 3—3 Fig. 1, this and the succeeding figures being enlarged from Figs. 1 and 2. Fig. 4 is a horizontal section on the line 4—4 Fig. 3. Fig. 5 is a vertical section on the line 5—5 Fig. 1. Fig. 6 is a horizontal section on the line 6—6 Fig. 5. Fig. 7 is an elevation of the track at the entering end of the switch. Fig. 8 is a cross-section on the line 8—8 Fig. 7, the switch-chair shown in

Fig. 7 being omitted; and Fig. 9 is a perspective view of the sole-piece shown in Fig. 8, and hereinafter more particularly described.

Like letters and numbers refer to like parts in all the figures.

The improved track shown in the drawings comprises box-rails A B and C of the construction set forth in my specification forming part of United States Patent No. 443,470, dated December 23, 1890, said rails A and B being of the shape known as "Section B" and shown in Figs. 1 to 5 of my drawings forming part of Patent No. 450,594, dated April 14, 1891, while said rail C is of the shape known as "Section C" and represented by Fig. 1 of the drawings of said Patent No. 443,470. Connecting these rails there is a tongue-switch mainly composed of a casting D, (Fig. 2,) which is approximately H-shaped in general cross-section, as shown in Figs. 3 and 5, and having a laterally swinging tongue E, which is pivoted by means of a pin 11, headed at its upper end, and provided at its lower end with a key 12, and the tongue is further provided on top at its pivot end with a customary projection 13 in continuation of a like projection 14 on the switch-casting, which in turn is a continuation of the guard 15 of the curve-rail C. The tongue E is supported by the horizontal web of the switch-casting; and the under side of this web is provided with a boss 16 to extend the bearing of the pivot pin 11 and coat with its key 12. The headed upper end of the pin 11 is flush with the tread surface 17 of the tongue, which in turn is flush with the treads 18 of the switch-casting and rails. The rails and switch in common are supported by clamp-chairs F F² F³ F⁴ F⁵, those beneath the switch-casting being each composed of a special chair-casting 19 fitted to the switch at a given point, a pair of clamps 20, and a through bolt 21 of proper length; the chair-castings 19 being in common of the construction represented in Figs. 3 to 6, while the clamps 20 are uniform, and the bolts 21 differ only in length. To coat with the clamps 20 of such clamp-chairs, the switch casting D is further constructed with longitudinal flanges 22 which project laterally at bottom, and are beveled on top, and is bifurcated at its broad end, and here provided

with flanges 22 within the fork as well as externally, so that each extremity is solidly supported by a special chair, F, F⁵, in addition to a sufficient number of intermediate chairs F² F³ F⁴. Each chair, in the drawings, is fastened down to a wooden cross-tie G by spikes H, Figs. 3 to 7, of the construction set forth in my specification forming part of Patent No. 447,268, dated February 24, 1891, 10 as shown distinctively in Figs. 3 and 5 and in Fig. 7. The spikes are omitted in Fig. 1. Each extremity of the switch-casting D is further constructed with an end-projection 23 fitted to the interior of the adjoining rail-end, and forming a solid seat for such rail-end. A sole-piece 24 (Fig. 9) abuts against each end-projection at the bottom of the latter, and is constructed with laterally projecting ends beveled at bottom so as to coact with a pair 15 of clamps 20^x and a through bolt 21^x, similar to the clamps 20 and bolts 21 of the chairs, in the manner represented in Figs. 7 and 8. A smooth and adequately supported joint is thus readily formed between the switch and each adjoining rail.

Different patterns of box-rails, clamps, chairs and spikes may obviously be employed without any material departure from this invention, and other like modifications will suggest themselves to those skilled in the art.

Having thus described the said improvement, I claim as my invention and desire to patent under this specification—

1. In street-railway track comprising box-rails and clamp-chairs, a tongue switch com-

posed principally of a casting approximately H-shaped in general cross-section, and provided at top with a laterally-swinging tongue, and at bottom with an internal boss integral with its horizontal web to coact with the pivot 40 of said tongue, and with external clamp-engaging flanges, substantially as hereinbefore specified.

2. In street-railway track comprising box-rails, a switch-casting provided at bottom with 45 longitudinal clamp-engaging flanges, and having a bifurcated broad end flanged within the fork as well as externally, in combination with clamp-chairs at the several extremities of the casting, and with intermediate clamp-chairs, substantially as hereinbefore specified.

3. In street-railway track comprising box-rails, a switch-casting having a bifurcated broad end, and provided at each extremity with an end-projection fitted to the interior 55 of an adjoining box-rail, substantially as hereinbefore specified.

4. In combination with a switch-casting having a suitable end-projection, and an adjoining flanged box-rail to the interior of which 60 said projection is fitted, a sole-piece abutting against the bottom of said projection and having beveled lateral ends, a pair of clamps engaging said lateral ends and the rail-flanges, and a horizontal bolt connecting said clamps, 65 substantially as hereinbefore specified.

WILLIAM CLARK WOOD.
